UNITED STATES PATENT OFFICE.

RICHARD SMITH, OF SHERBROOKE, QUEBEC, CANADA.

TREAD-SURFACE FOR FOOTWEAR.

1,160,206.

Specification of Letters Patent. Patented Nov. 16, 1915.

Application filed August 3, 1914. Serial No. 854,713.

To all whom it may concern:

Be it known that I, RICHARD SMITH, a citizen of the Dominion of Canada, and resident of the city of Sherbrooke, in the Province of Quebec and Dominion of Canada, have invented certain new and useful Improvements in Tread-Surfaces for Footwear, of which the following is a full, clear, and exact description.

10 This invention relates to improvements in soles and heels for footwear, and the object is to provide a simple and inexpensive anti-slipping device, which may be made an integral part of the footwear, or attached thereto at any time desired.

15 The device consists essentially of sheets of material which may be attached to the soles and heels of footwear, or may be the soles and heels themselves, and a plurality of 20 suction devices of flexible material carried by the sheets.

In the drawings which illustrate the invention:—Figure 1 is a bottom plan view of a boot arranged according to this invention.

25 Fig. 2 is a section on the line 2—2, Fig. 1.

Referring more particularly to the drawings, 11 designates the sole and 12 the heel of a boot, to each of which is attached a sheet 13 of suitable material, having circular flanges 14 of flexible material, such as rubber projecting from the surface thereof and forming a plurality of cups 15. When the wearer of the boot walks, the flanges flatten out with his weight, expelling the air from 35 the cups 15, so that a strong suction is produced between the sole of the boot and surface walked upon, which holds the flanges 14 and sole and heel tightly against the surface, and effectually prevents slipping by 40 reason of the frictional engagement. It is obvious that the smoother and therefore more slippery the surface, the better will be the suction, so that a person may walk easily even on wet ice, which is the most slippery surface commonly met with.

45 The circular flanges forming the suction cups may be made in a number of ways, of

which only a few are here illustrated and described. The most obvious method is to cast the flanges integral with a sole piece, as 50 shown in Fig. 2, or to insert plugs 16 in a punched sheet and secure the same by cementing, vulcanizing or other process. The sheet and plugs may be both of rubber of the same consistency, or the plugs may be 55 softer than the sheet. The plugs may also be plain cylindrical, or provided with flanges 17 on the upper end, so that if inserted in a leather sheet, entire dependence 60 will not be placed on cementing material. What is probably the cheapest method of all to make these soles, is to take a sheet of leather or other suitable material and punch 65 same from the upper side, so that holes 18, slightly conical, will be formed. Short lengths of rubber tubing 19 are inserted through the holes to form the flanges 14, and are secured by taper plugs 20 driven from the upper side. The sheet of leather thus treated may be a separate tap sole or 70 heel, as illustrated in Figs. 1 and 2, or may be the actual sole and heel themselves.

It will thus be seen that the invention may be put into practice in a great variety of ways, according to the fancy of the user, 75 and that the same results may be produced in many ways not illustrated, which, however, fall within the scope of the present invention.

Having thus described my invention, what 80 I claim is:—

A tread surface for footwear, comprising a sheet of material having a plurality of tapering apertures therein, and plugs inserted in said apertures, each comprising a 85 tubular member of resilient material, and a tapering core holding the same in the tapering apertures.

In witness whereof, I have hereunto set my hand, in the presence of two witnesses. 90

RICHARD SMITH.
